SPRAYER TANK

Lynn L. Fletcher, Lowell, Mich., assignor to
 Lowell Specialty Company, Lowell, Mich., a corporation of Michigan

Application February 14, 1947, Serial No. 728,611

2 Claims. (Cl. 222—540)

1

The invention relates to sprayer tanks and the like and, more particularly, to sprayer and similar apparatus tanks of the portable type, that is, those which are carried about by the person using them, adapted to hold several gallons of liquid such as stains, paints, oils, insecticides and other chemical preparations. Generally such tanks are carried by a suitable harness or by shoulder straps and are adapted to be put under substantial pressure through the medium of compressed air or other gas. In the embodiment chosen for illustration herein, the tank is equipped with a self-contained air pump, the arrangement and attachment mechanism for which form the subject matter of a co-pending application Serial No. 599,258, filed June 18, 1945, now Patent No. 2,529,645, and of which this application is a division. The embodiment hereof also includes a filling opening through which the liquid contents may be supplied and emptied and through which the particular pump barrel and associated parts are inserted and removed for assembly and disassembly, respectively, this subject matter being disclosed and claimed in a co-pending application, Docket No. 4649, Serial No. 721,400, filed January 10, 1947, now Patent No. 2,577,221, as a division of said application Serial No. 599,258.

One of the primary purposes of the invention herein disclosed, is to provide an arrangement whereby the nipple, by which a hose or flexible conduit is connected with the interior of the tank, is fully protected from injury during manufacturing operations, shipment and use, this objective also extending to protection of the hose or conduit end where it is connected with the nipple and to the clamping means or other arrangement whereby the conduit and nipple are secured or connected together. This feature is especially useful in portable sprayers since it prevents the conduit clamp, the conduit and nipple from catching on branches, vines and other obstructions, minimizes chances for dirt entering the container or tank when the conduit or hose is removed, and aids materially in guarding the nipple from injury during shipment.

Many other objects or purposes as well as the advantages of the invention will be readily appreciated and understood after reading the following description and claims and after viewing the drawings in which:

Fig. 1 is a side elevation of a spraying apparatus including a pressure tank embodying a preferred form of the invention;

Fig. 2 is a fragmentary elevation of the upper portion of the apparatus of Fig. 1, the view being

that of an observer standing to the left of Fig. 1; and

Fig. 3 is an enlarged view in section taken along the section line 3—3 of Fig. 2, looking in the direction of the arrows.

The liquid container is of generally cylindrical form and may be composed of a cylindrical central section 2 of relatively light sheet metal, and top and bottom sections 3 and 4 of substantially heavier sheet metal to withstand the blows and impacts to which the container may be subjected in use. The top and bottom sections may be secured to the central section by riveting or soldering or in any other suitable manner to effect fluid tight joints under such pressures as those to which the container may be subjected. Lightness is an important feature for portable containers but they must also be leak-proof and able to withstand severe use.

A self-contained pump, the barrel or cylinder of which is designated 5 and the handle for the piston of which is designated 6, is mounted in and through the top section 3 and firmly secured thereto. The construction of the pump mounting and the method by which it is assembled in the tank or container through a fill opening adapted to be tightly sealed by a closure or cover 7, are more fully described in said application Serial No. 599,258. The cover 7 has a floating hinge connection comprising hooks 8 (one only shown) and eyelets, through which the hooks pass, in a bracket 9 secured to the top of section 3. When the cover is released to uncover the fill opening it may depend into the container as indicated in dotted lines in Fig. 3.

Liquid to be sprayed is loaded into the container, through the fill opening, to some predetermined level whereupon the cover 7 is secured over the opening and the container and its contents are put under pressure by operation of the air pump. The air under pressure in the upper portion of the container will tend to displace the liquid through a discharge pipe or tube 11 which leads to the exterior of the container where it terminates in a nipple 12 adapted to be received within a base or flexible conduit 13 which, in turn, leads to a spray nozzle (not shown). A hose-clamp or other similar device 14 may be used firmly to secure the conduit to the nipple.

Prior to this invention, the pipe or tube 11 has been extended through the container wall so that its terminal or nipple end was disposed in the open or outside and beyond the wall surface area of the container. Thus situated the nipple, the connecting end of the flexible conduit or hose and any hose clamp were openly exposed to vari-

ous hazards. Vines and branches not infrequently caught on the hose and hose clamp at the connection tending not only to effect disconnection of hose and nipple thus permitting loss of the container contents, but could injure the nipple in such manner as to cause the connection to leak. Furthermore, if, as during shipment, repair or accident, the hose or flexible conduit should be detached from the nipple, there was nothing to prevent dirt and debris from lodging in the nipple and entering the tank or container, or, to prevent serious injury to the nipple. These as well as other objections and undesirable possibilities are entirely avoided or obviated by our arrangement by which the nipple is located and terminates wholly within the general confines of the container or tank wall and by so relating the nipple to the tank wall that it has a structural security and a security safety factor equal to if not greater than any prior type of construction despite an axial inclination of the nipple at an acute angle to the axis of the tank. Of course, the termination of the nipple within the general confines of the tank wall will also fix the location of the hose or conduit end and the hose clamp in the same place.

These ends are attained by cutting away the container or tank wall as indicated at 15 in Figs. 2 and 3, shaping a piece of sheet metal to form a flanged cup generally designated 16 and securing the flanges 17 by soldering or otherwise to the margins defining the peripheral edges of the tank wall about the opening 15. It is preferable that the bottom wall 18 of the cup be so formed that it be inclined (at least in the plane of the section of Fig. 3) at an acute angle to a plane normal to the axis of the tank and that the other wall 19 (at least in the plane of the section of Fig. 3) be disposed approximately at a right angle to the bottom wall 18. From such midsections of the walls 18 and 19 these walls may be shaped in any suitable form and manner to abut the flanges 17 against the inner surfaces of the tank sections, as will be understood.

The bottom wall 18 of the cup 16 is drilled or punched as indicated at 21 for the discharge pipe or tube 11 which extends to a place closely adjacent to but spaced from the bottom of the tank and is secured in position by a clip 23 riveted or otherwise secured to the tank side wall as indicated at 24. Where the tube 11 passes through the wall 18 it is soldered or otherwise secured thereto in such a manner as to provide a leak-proof joint 25. Preferably the axis of the tube 11 is disposed at right angles to the illustrated section of wall 18. The outer end portion of tube 11 provides a coupling nipple 12 adapted to be inserted within the end portion 27 of a rubber or other hose or flexible conduit which may be firmly secured to the nipple by a hose clamp 14.

The construction and arrangement thus provided furnishes a most satisfactory solution to problems heretofore encountered. By reason of disposition of the nipple 12 wholly within the recess formed by cup 16 the nipple is protected against injury and dirt; likewise the hose or conduit end 27 and the hose clamp 14 or other fastening means are similarly situated and protected. Branches and vines are prevented from snagging on or directly contacting the nipple, connecting conduit end and clamp. Furthermore, the angular relationship of the walls of cup 16 and the angular disposition of the tube 11 and nipple 12 determine the desired angle at which 75

the nipple and hose or conduit initially project from the spray tank while, at the same time, give maximum structural strength. The recess provided by the cup 16 will be made of such dimensions as to permit the necessary access to effect coupling and uncoupling between the conduit and nipple.

Since the details of construction and arrangement may be varied over a wide range without departing from the fundamentals of the invention, we desire to be limited only by those fundamentals as defined in the following claims.

I claim:

- 15 1. In a portable spraying apparatus, a fluid container having a substantially cylindrical side wall, a portion of said wall between the container ends being reentrant to provide a recess opening to the exterior of the container, said reentrant portion including a wall part inclined inwardly and toward one end of the container and inclined in a plane which is at angle to the cylinder axis and a second wall part substantially at right angle to the first said wall part, the second wall part being inclined inwardly and toward the other end of the container, and a relatively rigid conduit extending through and rigidly secured to one of said wall parts with its ends projecting beyond the opposite sides of said last mentioned wall part with one end projecting into the recess, the portion of said conduit which extends through one of said wall parts being inclined at an angle to the longitudinal axis of said container, a nipple provided on the end of the conduit projecting into the recess and extending substantially parallel to the other of said wall parts with said nipple disposed substantially wholly within the bounds of said recess, and the other end of said conduit projecting into and extending to adjacent the bottom of the container.
- 20 2. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 25 3. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 30 4. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 35 5. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 40 6. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 45 7. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 50 8. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 55 9. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.
- 60 10. In a portable spraying apparatus, a fluid container having a substantially cylindrical side wall, a portion of said wall being reentrant to provide a recess opening laterally to the exterior of the container, said reentrant portion including two inwardly extending wall parts both inclined to the side wall and said wall parts extending in planes which are at substantially a right angle to each other, one of said wall parts having an aperture therethrough, a tube projecting through the aperture with its opposite ends extending beyond the opposite sides of the apertured wall part, the portion of said tube which projects through said aperture being inclined at an angle to the longitudinal axis of said container, one end of the tube terminating in the recess and the other end extending into the container, and a hose connecting nipple on the end of the tube terminating in the recess providing an outlet from the interior to the exterior of said container, said nipple having its hose connecting terminal end disposed wholly within the bounds of said recess and its axis substantially perpendicular to the apertured wall part.

LYNN L. FLETCHER.
